COMBINED CRIB AND TOP THEREFOR

Gretchen G. Verner and James M. Verner, both of 3618 N. Nelson St., Arlington, Va. 22207

Filed July 5, 1967, Ser. No. 7,713

Term of patent 14 years

(Cl. D5—5)

FIG. 1 is a front perspective view of a combined crib and top therefor showing our design;

FIG. 2 is a rear perspective view of the combined crib and top therefor with the top thereon;

FIG. 3 is an exploded rear perspective view; and

FIG. 4 is a rear perspective view of the combined crib and top therefor with the top removed.

We claim:

The ornamental design for a combined crib and top therefor, as shown.
